UNITED STATES PATENT OFFICE

132,523

DESIGN FOR AN EARRING OR SIMILAR ARTICLE

Abraham Gerstenzang, New York, N. Y.

Application April 27, 1942, Serial No. 106,713

Term of patent 3½ years

To all whom it may concern:

Be it known that I, Abraham Gerstenzang, a citizen of the United States, residing in New York city, in the county of New York and State of New York, have invented a new, original, and ornamental Design for an Earring or Similar Article, of which the following is a specification, reference being had to the accompanying drawing, forming part thereof.

Fig. 1 is a plan view of an earring or similar article showing my new design, and
Fig. 2 is a rear view of Fig. 1, and
Fig. 3 is an elevational side view thereof.

I claim:
The ornamental design for an earring or similar article, substantially as shown.

ABRAHAM GERSTENZANG.
